[57] CLAIM

The ornamental design for long pants, as shown and described.

DESCRIPTION

FIG. 1 is a front perspective view of long pants showing my design, the left leg of the pants being shown in a position forward of the right leg, the left and right legs being turned slightly towards the left side, and the portion of the left leg which is not visible being a mirror image of the opposite leg; FIG. 2 is a left side perspective view of the long pants of FIG. 1; FIG. 3 is a right side perspective view of the long pants of FIG. 1; and, FIG. 4 is a rear perspective view of long pants showing my design, viewed from the rear and slightly to the right, with the right leg shown in a position forward of the left leg.
